UNITED STATES PATENT OFFICE.

GEORGE F. HUTCHINS, OF WORCESTER, MASSACHUSETTS, ASSIGNOR TO THE KNOWLES LOOM WORKS, OF SAME PLACE.

PATTERN MECHANISM FOR LOOMS.

SPECIFICATION forming part of Letters Patent No. 398,328, dated February 19, 1889.

Application filed November 10, 1888. Serial No. 290,419. (No model.)

To all whom it may concern:

Be it known that I, GEORGE F. HUTCHINS, a citizen of the United States, residing at Worcester, in the county of Worcester and State of Massachusetts, have invented certain new and useful Improvements in Pattern Mechanism for Looms; and I do hereby declare that the following is a full, clear, and exact description thereof, which, in connection with the drawings making a part of this specification, will enable others skilled in the art to which my invention belongs to make and use the same.

My invention relates to looms, and more particularly to the harness and drop-box mechanism of the well-known Knowles loom shown and described in Letters Patent of the United States No. 134,992.

The object of my invention is to secure a greater range of adjustment in timing the parts of the harness and drop-box mechanism than has heretofore been practicable in said loom, while retaining all the facilities for manipulating the harness and box motions by hand that have been obtained in said loom; and my invention consists in certain novel features of construction, arrangement, and combination of mechanisms, as will be hereinafter fully described.

Referring to the drawings, Figure 1 is a partial side elevation of said Knowles loom with my improvements applied thereto. Fig. 2 is a section taken on line *x x*, Fig. 1. Fig. 3 is a detail view of the sliding key. Fig. 4 is a section taken on line *y y*, Fig. 1; and Fig. 5 is a representation, largely diagrammatic, of some of the working parts of the mechanism.

In the accompanying drawings, 1 is a part of the loom frame or arch. 2 is the head-frame. 3 is the top and 4 the bottom cylinder-gear, journaled in the head-frame. 5 is a vibrator-gear pivoted at 6 on the vibrator-lever 7, which is pivoted at 8 in the head-frame. 9 is a vibrator-connector pivoted at one end to the gear 5 and at the other end to a harness-lever, 10. 11 is the pattern-cylinder. 12 is the lock-knife arm pivoted on shaft 13, journaled in the loom-frame and operated through lever 14 by cam 15 on the lower cylinder-shaft. 16 is a handle fast on the top

cylinder-shaft, by means of which the head motion is turned by hand, the cylinders being geared to the upright driving-shaft, as shown in Fig. 3 in the above-mentioned Patent No. 134,992. All these parts are constructed and arranged as heretofore and as fully set forth and described in said Patent No. 134,992.

Referring to Fig. 2, 4 is a part of the lower cylinder, 2 a part of the head-frame, 17 the cylinder-shaft, and 15 the lock-knife cam fast on said shaft.

Loose on the end of the cylinder-shaft 17, and adjoining the lock-knife cam 15, is a spur-gear, 18, which meshes with a gear, 19, of the same size loose on the stud 20, fast in frame 2. Fastened to gear 19 is a smaller gear, 21, in line with a fourth gear, 22, of the same size as the gear 21, loose on shaft 17 and adjoining the first-mentioned gear 18. Gears 21 and 22 are smaller than gears 18 and 19, so that when the latter pair are meshed properly the points of the teeth of the former pair clear each other.

Gears 18 and 22 are retained on the shaft by collar 23, and are slotted to receive the projecting end 24 of the key 25, (shown in detail in Fig. 3,) adapted to slide freely in a slot in the end of shaft 17, and provided with a head, 26, by which it may be moved in its slot out of engagement with one and into engagement with the other of gears 18 and 22. Fastened to collar 23 and coiled part way around it is a flat spring, 27, (see Fig. 1,) which acts to force a pin, 28, free to move in a hole in collar 23 into notches 40 in the top of key 25. The notches 40 are so placed that the pin 28 will hold the key 25 in the proper position for driving one or the other of the gears 18 and 22 with the shaft 17.

Mounted loosely upon a stud, 29, Fig. 1, fast in frame 2, is a gear, 30, of the same size as gears 21 and 22, and so placed as to mesh properly with them. Fast on the face of gear 30 is a pin-wheel, 31, fitted to drive the star-wheel 32, loose on the end of pattern-chain cylinder-shaft 11.

Formed in the face of the star-wheel, on a circle concentric with it, are sockets 33, placed at regular intervals between the points of the

star-wheel, and adapted to receive the end of plunger 34, fitted to slide in chamber 35, which is part of the hub 36, fastened by set-screw 37 to the end of the pattern-cylinder shaft 11. 5 (See Fig. 4.)

Plunger 34 is reduced in diameter on its inner end, having coiled about it the spiral spring 38 confined between the shoulder at the end of the plunger and the end of the 10 chamber 35, thus acting to force the plunger into the sockets 33 on the star-wheel 32. The reduced spindle of the plunger projects out through the end of the chamber, and receives the handle 39, by which the plunger is drawn 15 out of the sockets 33 in the star-wheel 32, and by which the pattern-cylinder 11 may be turned by hand, while the star-wheel 32 is locked to the gearing-train by the pin-wheel 31. When the plunger 34 is in a socket 33, 20 the star-wheel 32 drives the pattern-cylinder 11 with it.

Referring to Fig. 5, I will explain the operation of the mechanism there shown. The cylinder-gears 3 and 4 rotate in the direction 25 indicated by the arrows. The vibrator-gear 5 is represented as just at the point of being started by the lower cylinder-gear, 4, the revolution of which turns the vibrator-gear through about a half-revolution, bringing the 30 opposite end of slot 40 in the vibrator-gear against the stop 41 on the vibrator-lever 7, and bringing the open part 42 of the gear 5 opposite the point of contact with gear 4, so that the vibrator-gear 5 will not again be 35 moved till the vibrator-lever 7 is lifted by the pattern-cylinder 11 into engagement with the top cylinder-gear, 3, when the contrary half-revolution of the vibrator-gear 5 takes place, and it remains in that second position till the 40 pattern-cylinder drops the vibrator-lever 7 into the position shown in Fig. 5, and so on, as fully set forth in said Patent No. 134,992.

It is desirable to take as large a part of the revolution of the cylinder-gears as possible for the rotation of the vibrator-gear in order to make the harness motion easy on the warps.

Heretofore the pattern-cylinder had been driven continuously by gearing from the end 50 of the lower cylinder-gear shaft, 17, Fig. 2, the gearing being in such proportion that one revolution of the cylinder-gear shaft moves the pattern-cylinder one angular space equal to one space on the star-wheel. By substituting the pin-wheel and star-wheel for the continuous gearing I am enabled, with an equally 55 easy motion, to change the pattern-cylinder more quickly, thus getting more time for ad-

justment of the harness and box motion cylinder-gears—an advantage which is well understood by those skilled in the art. 60

It is frequently desirable in finding the pick, and in picking out imperfect work, to open the successive sheds in the inverse order to that used in weaving. 65

It will be seen by reference to Fig. 5 that the cylinder-gears cannot be turned backward. Suppose the cylinder-gears to be started in a direction opposite to the proper one indicated by the arrows until the teeth 43 on the cylinder-gears engage the teeth 44 on the vibrator-gear 5; then the motion would be locked, as the vibrator-gear cannot turn against the stop 41. By pulling out the head 26, Figs. 1 and 2, until the projecting part 24 70 of key 25 engages the gear 22, said gear becomes the driver on shaft 17, leaving gear 18 loose, by which change the pin-wheel 31 will be driven direct from shaft 17 instead of through intermediate gears, 19 and 21, thus reversing 80 the motion of the pattern-cylinder 11, while the cylinder-gears 3 and 4 turn in the same direction as before.

Having thus described my invention, what I claim as new, and desire to secure by Letters Patent, is— 85

1. In a loom of the class described, the combination, with the cylinder-gears, vibrator-gear, connector, vibrator-lever, and harness-lever, and gears 18 and 22, loose on the lower 90 cylinder-shaft, sliding key 25, compound gears 19 and 21, loose on a stud supported in the loom-frame, of a pin-wheel gear, and pin-wheel driven by said gears, and adapted to drive a star-wheel connected with the pattern-cylinder, 95 and said star-wheel and pattern-cylinder, all constructed and arranged substantially as shown and described.

2. In a loom of the class described, the combination, with the pattern-chain cylinder, a star-wheel, 32, loose on said cylinder, hub 36, fast thereon, and a spring-actuated plunger supported in said hub and adapted to enter into and be withdrawn from sockets in said star-wheel, for the purpose stated, of a pin-wheel, 31, and gear 30, loose on a stud, compound intermediate gears, 19 and 21, loose on a stud, gears 18 and 22, loose on the cylinder-gear shaft, and said shaft, sliding key 25, cylinder-gears, connector, vibrator-gear, vibrator-lever, and harness-lever, substantially as shown and described. 105 110
